UNITED STATES PATENT OFFICE.

FERNANDIZE M. SIMMONDS, OF CHICAGO, ILLINOIS, ASSIGNOR OF ONE-HALF TO RAYMOND B. DONALDSON, OF CHICAGO, ILLINOIS.

SPRING.

No. 872,692.

Specification of Letters Patent.

Patented Dec. 3, 1907.

Application filed February 28, 1906. Serial No. 303,395.

To all whom it may concern:

Be it known that I, FERNANDIZE M. SIMMONDS, a citizen of the United States, and a resident of the city of Chicago, in the county of Cook and State of Illinois, have invented certain new and useful Improvements in Springs; and I do hereby declare that the following is a full, clear, and exact description of the same, reference being had to the accompanying drawings, and to the letters of reference marked thereon, which form a part of this specification.

This invention relates to improvements in springs and more particularly to a single leaf spring of that class known as vehicle springs though obviously it is adaptable for many other purposes.

Heretofore difficulty has been found in producing a satisfactory single leaf spring owing to the fact that it was thought that the leaf must necessarily be made very light to afford the desired degree of resiliency. Such springs usually soon lose their resiliency and become unsatisfactory and useless.

The object of this invention is to provide a cheap, simple and durable construction in which a leaf spring consisting of one or more leaves or sections may be made of any desired strength or degree of resiliency without interfering with the lasting power of it.

The invention consists in the matters hereinafter described and more fully pointed out and defined in the appended claims.

In the drawings: Figure 1 is a side elevation of a device embodying my invention. Fig. 2 is an enlarged side elevation of one end of the spring showing the leaves broken away. Fig. 3 is a top plan thereof. Fig. 4 is a vertical central section of the same, and, Fig. 5 is a fragmentary sectional view illustrating a modified form of construction.

As shown in said drawings: Referring first to Figs. 1 to 4 inclusive A and A' represent respectively the upper and lower leaves or members of an elliptical spring for a vehicle or the like. Each of said leaves or members comprises a resilient bar provided at its ends with yoke arms indicated respectively by a—a' and in which are provided transverse journal bearings comprising as shown U shaped lugs a²—a³ each opening inwardly of the spring or towards the opposite leaf and apertured to receive cotter pins or the like a⁴.

A downwardly opening casing or housing B is pivoted as shown at each end of the leaf

or member A by means of laterally directed studs b formed integrally with said housing and arranged on opposite sides thereof which engage in the bearing lugs a² and are held therein by means of the cotter pins a⁴. Said housings are permitted a given amount of swing in said bearings which is limited however by means of the upwardly and downwardly extending lugs a⁵—a⁶ on the leaf adjacent the crotch of each yoke and which as shown are rounded on their faces adjacent said housings to permit the housings to swing within certain limits. Each of said casings or housings B as shown is provided in the top thereof with a screw threaded aperture in which is engaged an externally threaded nut b² which is held in place by a lock nut b³ having threaded engagement thereon. Said nut b² as shown is cored on its under side to provide a seat and is provided therethrough with a central threaded aperture, and having threaded engagement in said aperture is a shaft or bolt C which extends axially of said housing B and protrudes from the lower end thereof.

Supported on each end of the leaf or member A' is a housing B' which as shown is of a diameter to fit within the housing B and to telescope therewith and which, as shown, is provided with integral studs b³ adapted to engage in the bearings a³ in the yoke arms a'. Each of said housings B' as shown is cored to provide an axial sleeve b¹ extending upwardly from the bottom and adapted to receive the shaft or bolt C and in the annular recess about the same is seated the coil spring D, the upper end of which engages in the seat in the nut b². Said shaft C as shown projects below the housing B' and is provided on its lower end with a nut c and a set nut c' between which and the bottom of the housing B' is a coiled spring C' forming a resilient stop for the outward throw of said housings.

In the construction shown in Fig. 5 the housings B² and B³ are formed integrally with the leaves A² and A³ and are telescopically engaged to receive the coiled springs D as before described. The upper housing B² is provided in its top with a screw threaded aperture in which engages an externally threaded nut b⁵ as before described which affords a seat for the upper end of said spring D. The lower housing B³ is provided on its upper end with a rounded or spherically shaped portion b⁷ which fits within the hous-

ing B² and permits of considerable angular movement of one housing with respect to the other thereby preventing said housings from binding when load is added to the leaves A² 5 and A³.

The operation is as follows: Referring first to the construction shown in Figs. 1 to 4 inclusive it is obvious that owing to the pivotal connection between the housings B and B' 10 with the leaf springs A and A' that the housings will readily adjust themselves to each other when load is added to said leaf springs. The coiled springs D, which are strong enough to withstand the load transmitted to 15 them from the leaf springs, act normally to hold the housings extended, while the bolts or shafts C hold the housings assembled.

Should the springs D become weak or broken they may be removed by simply re- 20 moving the bolt C thereby permitting the housings to be taken apart or if preferred a support may be placed beneath the leaf A to hold it from dropping and the nut b² removed thereby affording access through the top of 25 the casing.

In the construction shown in Fig. 5 in which the housings are shown integral with the leaves, the rounded point of contact or bearing between the housings permits them 30 to move freely when the leaves are depressed.

Obviously a single leaf spring constructed in accordance with my invention affords a maximum amount of resiliency and the cost of which owing to its simple construction is 35 reduced to a minimum. It is also obvious that, inasmuch as the spring can be quickly assembled and any part removed and replaced or repaired, should it become necessary repairs can be much more quickly and 40 easily effected than with leaf springs as heretofore constructed with a plurality of leaves.

I claim as my invention:

1. In a device of the class described the combination with a downwardly opening upper casing, lugs integral therewith, a leaf spring engaged at one end to said lugs, an upwardly opening casing telescoping the upper casing, lugs integral therewith, a leaf spring engaged to said lugs, a sleeve integral with 45 50 and extending upwardly from the lower casing, a spring in said casing around said sleeve and bearing against the upper casing and a bolt extending through said upper casing and sleeve.

2. In a device of the class described the combination with an upper and lower housing, lugs on each, leaf springs one engaged at its end to each housing, a sleeve extending upwardly from the bottom of the lower housing, a bolt extending through the upper housing and sleeve and projecting beyond the lower housing, a spring inclosed by said housings and a spring on said bolt pushing upward against the lower housing.

3. In a device of the class described the

combination with telescoping housings of a leaf spring pivotally engaged to each housing, a sleeve concentric with one of said housings affording a space between the same, a spring in said housing around the sleeve, a rod extending below the housing, a stop thereon and a spring engaged on said rod adapted to force the lower housing upwardly.

4. The combination with oppositely disposed leaf springs of interfitting, telescoping parts pivoted on the ends thereof, resilient means concealed therein and acting to force the leaves of the spring oppositely and means on each end of the upper leaf spring adapted to limit the swinging movement of the telescoping parts

5. The combination with the oppositely disposed leaves of a leaf spring of downwardly opening casings or housings on the ends of one of said springs and upwardly opening casings on the ends of the other adapted to telescope within the upper casings, a spiral spring concealed in the housing thus formed and bearing at its ends against the top and bottom of the housing and a lug on each end of the upper leaf spring adapted to limit the swinging movement of the casing.

6. In a device of the class described the combination with telescoping casings or housings, of projections integral with each casing near one end thereof on diametrically opposite sides, oppositely disposed spring leaves engaged at their ends on said projections, a spring inclosed by said casings adapted to force the same to their outward limit of movement, a shaft extending axially through said casings and projecting beyond one of the same and a spiral spring on said shaft outside the casing bearing against the same.

7. In a device of the class described the combination with telescoping housings or casings of outwardly projecting studs integral therewith on opposite sides of said casings, a leaf spring having each end forked to pivotally engage said studs, and a spring inclosed by said casings and holding the same at their outer limit of movement.

8. The combination with oppositely disposed leaf springs of telescoping housings pivoted on each end thereof, coiled springs in said housings and lugs on each end of the upper leaf spring limiting the movement of the housings.

9. In a device of the class described the combination with oppositely disposed leaves of telescoping housings pivotally supported on the ends thereof, coiled springs in said housings and means limiting the outward movement of said housings with respect to each other.

10. In a device of the class described the combination with oppositely disposed leaves, of telescoping members pivotally engaged on the ends of said leaves, coiled springs con-

sealed in said telescoping members, a bolt rigidly engaged in one telescoping member and extending through the other and a spring on the outer end of said bolt acting to hold said members together.

11. In a device of the class described the combination with oppositely disposed leaf springs of upper and lower telescoping housings pivoted on the ends thereof, a coiled spring in the housings on each end of said leaves, a shaft rigidly engaged in the end of

one of said housings and extending axially thereof and through the other and a spring on the outer end of said shaft acting to force said housings together.

15

In testimony whereof I have hereunto subscribed my name in the presence of two subscribing witnesses.

FERNANDINE M. SIMMONDS.
